UNITED STATES PATENT OFFICE.

CLIFFORD V. HOUK AND THOMAS W. BERRY, OF SAN DIEGO, CALIFORNIA; SAID BERRY ASSIGNOR OF ONE-THIRD OF HIS RIGHT TO SAID HOUK.

RAILWAY-CROSSING.

1,389,560.

Specification of Letters Patent. Patented Aug. 30, 1921.

Application filed May 27, 1920. Serial No. 384,581.

To all whom it may concern:

Be it known that we, CLIFFORD V. HOUK and THOMAS W. BERRY, citizens of the United States, residing at San Diego, in the county of San Diego and State of California, have invented certain new and useful Railway-Crossings, of which the following is a specification.

Our invention relates to railway crossings, more particularly to mechanical means operated by the approaching vehicle for turning and positioning the groove at the joint of the crossing for taking the flange of the wheel so that the extraordinary noises and jars are eliminated at crossings and the objects of our invention are: first, to provide a railway crossing so constructed that the track upon which the base of the wheel rolls is level in the direction the vehicle is going; second, to provide a railway crossing of this class in which the joint at the intersection of the grooves for taking the flange of the wheel is provided with a revolute member provided with a single groove adapted to be turned in alinement with the direction the vehicle is approaching the crossing; third, to provide a railway crossing of this class in which said revolving parts are locked securely in their position for receiving the flange of the wheel and remain in locked position until released by a vehicle coming from another direction; fourth, to provide a railway crossing of this class in which the operating mechanism is actuated by a releasing lever engaged by the vehicle wheel which unlocks the revolute member, then immediately operating a lever which revolves the revolute member a one quarter revolution positioning it in alinement with the approach of the vehicle and locking it in position and locking the operating levers in inoperative position; fifth, to provide a railway crossing of this class which is made up of units so that it is operative with single or double crossings as desired, each unit consisting of the four intersecting points and the four intersecting points connected so that they operate in unison and sixth, to provide an apparatus of this class which is simple and economical of construction, durable, easy to install, positive in its action, which will not readily deteriorate or get out of order and

on which the vehicle rides on the face of the wheel at all times and not on the flange as in some devices of this class.

With these and other objects in view as will appear hereinafter our invention consists of certain novel features of construction, combination and arrangement of parts and portions as will be hereinafter described in detail and particularly set forth in the appended claims reference being had to the accompanying drawings and to the characters of reference thereon which form a part of this application in which:

Figure 1 is a top or plan view of a double crossing showing two units of the operating apparatus only; Fig. 2 is a sectional view through 2-2 of Fig. 1 on an enlarged scale showing the details of the operating mechanism; Fig. 3 is a sectional view through 3-3 of Fig. 2; Fig. 4 is a plan view of the crossing shown upside down from its normal position and showing the operating mechanism fragmentarily; Fig. 5 is a bottom view of one of the units in a slightly modified form from that of the other views of the drawings and Fig. 6 is a similar view of the same in another modified form.

Similar characters of reference refer to similar parts and portions throughout the several views of the drawings.

The rail frame 1, revolute member 2, disk 3, ball arm 4, connecting rod 5, levers 6, 7 and 8, link members 9 and 10, link 11, releasing lever 12, connecting rod 13, lever 14, support 15, latch member 16, spring 17 and connecting rods 18 constitute the principal parts and portions of one unit consisting of the four intersecting points of the crossing and the operating mechanism.

The rail frame 1 is of the conventional type of railway crossing frame work. The point of intersection of the grooves is eliminated however and there is provided a revolute member 2 positioned directly at the intersecting point of the flange grooves. This revolute member 2 is cylindrical in form and of greater diameter at its upper end than at its lower end and is positioned in a conforming recess in the intersecting point of the crossing so that its upper surface is flush with the upper surface of the rail and it is provided with a groove ex-

tending across the face conforming to the groove in the rail.

It will be noted that the rail joint at the intersection of the various members of the frame is enlarged at these intersections for reinforcing and supporting this revolute member 2. It is provided on the lower face of the rail member with a collar 2^a for holding it securely in position and preventing its rising in the rail. Secured on the lower end of this revolute member 2 is the disk member 3 which is provided in one side with a notch 3^a shown best in Fig. 4. Secured to this disk member is an arm 4 which is provided with a ball on its extended end adapted for connection with the connecting rod 5 at one of its ends and the opposite end of the connecting rod 5 connects with the free end of lever 6 which is pivotally mounted at its opposite end on the frame 1. Pivotally connected to this lever 6 intermediate its ends is a link member 9 and the opposite end of the link member 9 is pivotally connected to the free end of a lever 7 which is also pivotally mounted at its opposite end on the frame 1 and pivotally connected to this lever 7 intermediate its ends is another link member 10, the opposite end of which is pivotally connected to a lever 8 which is one of the actuating levers for revolving the member 2 and this lever is pivotally mounted on the frame 1 intermediate its ends at a point 1^a and its short end extends to a position near the face of the rail, when in operative position. Intermediate this pivotal mounting 1^a and the connection of the link 10 this lever 8 is provided with a pin 8^a on which is mounted the link 11 by means of a slot 11^a which permits certain longitudinal shifting of the link 11 relatively to the lever 8. The opposite end of this link 11 is pivotally connected to another operating lever 12 which performs the primary function of releasing the latches before the revolution of the revolute member 2. This lever 12 is pivotally mounted at a point 1^b on the frame 1 and it is preferably provided with a curved portion 12^a which extends to flush with the top of the rail when in operative position 50 and is adapted to receive the wheel flange for depressing the portion 12^a and operating the lever 12. Pivotally connected between the point 1^b and the long end of the lever 12 is the rod 13 which extends some distance past the revolute member 2 and is pivotally connected to a lever 14 which is pivotally mounted intermediate its ends upon a support 15 which support 15 is secured to the frame 1 and to the same end of the lever 14 55 that the rod 13 is connected is secured a tension spring 17 which is also secured to the frame at its opposite end at a point 1^c. The opposite end of this lever 14 is provided with a projecting pin 14^a which is adapted 60 to operate in a slot 16^a in the latch 16 which

is pivotally mounted on the frame 1 at a point 1^d, thus providing for the shifting of the free end of the latch 16 with the movement of the lever 14 by means of the rod 13 and lever 12.

Thus it will be noted that when the flange of the wheel engages the portion 12^a of the lever 12 said portion is depressed throwing the opposite end of the lever 12 backwardly shifting the rod 13, longitudinally extending the spring 17 and shifting the latch 16^a out of engagement with the notch 3^a at the same time the link 11 engages the pin 8^a and partially revolves the member 2 through the multiple levers and connecting rods as hereinbefore described so that the latch will not again engage the notch and as the wheel passes onward it engages the short end of the lever 8 which revolves the member 2 a remainder of a quarter of a revolution so that the groove in the member 2 is in a position at a direct right angle to its former position and ready to receive the flange of the wheel in its passage over the intersection of the rail joint and that the upper ends of the levers 8 and 12 will remain depressed and inoperative position until released by a vehicle approaching in another direction.

The revolute members 2 of the four intersections of the rails which would form an ordinary single rail crossing are connected together in unison so that the four members revolve together by means of rods 18 which are provided with turn buckles for adjusting them to proper lengths so that when one of the revolute members 2 of said unit revolves the other three likewise revolve. However, in Fig. 5 there is provided means for connecting these units by means of a chain which connect with these disks 3 for operating them in unison and in Fig. 6 is disclosed a belt for performing the same function, the object being simply to operate the four so that they revolve in unison with the revolution of one.

In a double crossing as shown in Figs. 1 and 4 of the drawings there are used eight units of the operating mechanism for revolving the revolute member 2, for instance as shown in Figs. 1 and 4, the one unit on the approach side connects with the first unit the one in connection with the other rail connects with the second unit so that there are two of these operating units at each approach side of a double railway crossing, the rods 13 being extended to the proper position for connecting with one of the members 8 of each unit for releasing and partially revolving and the rod 5 similarly connected for revolving the remainder of the quarter revolution, it being noted that the revolute members 2 revolve back and forth on a quarter revolution depending on the approach of the vehicle to the crossing.

It will be noted that all of the connecting

rods are provided with turn buckles for adjustment to provide the proper movement of the different revoluble members.

Though we have shown and described a particular construction, combination and arrangement of parts and portions and a certain modification thereof we do not wish to be limited to this particular construction, combination and arrangement nor the modification thereof but desire to include in the purview of our invention the construction, combination and arrangement substantially as set forth in the appended claims.

It is obvious that with this construction there is provided a railway crossing in which the intersection of the grooves for receiving the flange of a vehicle wheel are revolved by the vehicle in its approach to the crossing so that the face of the wheel rides on a level plane in crossing the intersection of the rails and grooves of a railway crossing.

Having thus described our invention what we claim as new and desire to secure by Letters Patent is:

1. A railway crossing, including a rail frame work, a revoluble member positioned at each rail intersection, compound lever and connecting means in connection with four of said revoluble members adapted to be engaged by the flange of the vehicle wheel as it approaches said crossing for separately and progressively revolving four of said revoluble members simultaneously a portion of a revolution and latch means in connection with said revoluble member operated by a portion only of said lever mechanism for supporting said revoluble member in a certain position and for releasing the same upon the approach of a vehicle.

2. A railway crossing, including a frame work of railway rails provided with flange grooves therein, a revoluble member with a single groove mounted at each intersection of said railway rails, a multiple lever and connecting means actuated by the vehicle wheel for separately and progressively revolving four of said revoluble members simultaneously a portion of a revolution only with the approach of the vehicle and means in connection with a portion only of

said multiple lever means for locking said revoluble member in its turned position whereby said levers are held in a position not engageable by other vehicle wheels until released by a vehicle going in another direction.

3. A railway crossing, including a frame work of intersecting rails, a revoluble member forming the intersecting portion of said rails provided with a groove conforming to the grooves for taking the flange of the wheel in said rail, an extended member connected to said revoluble member below said rails, a lever pivotally mounted upon the rail engageable by the wheel, means connecting said lever with said extended member whereby said extended member is revolved with the movement of said lever by the wheel, a latch adapted to engage said extended member and hold it in certain position and another lever adapted to be engaged by the wheel for operating said latch and slightly revolve said extended member.

4. A railway crossing, including a frame work of intersecting rails, a revoluble member forming the intersecting portion of said rails provided with a groove conforming to the grooves for taking the flange of the wheel in said rail, an extended member connected to said revoluble member below said rails, a lever pivotally mounted upon the rail, engageable by the wheel, means connecting said lever with said extended member whereby said extended member is revolved with the movement of said lever by the wheel, a latch adapted to engage said extended member and hold it in certain position, another lever adapted to be engaged by the wheel for operating said latch and means connecting said levers whereby one of said levers is slightly operated with the movement of said latch operating lever and a partial movement of said extended member is effected.

In testimony whereof, we have hereunto set our hands at San Diego, California, this 20th day of May 1920.

CLIFFORD V. HOUK.
THOMAS W. BERRY.
